DESIGN FOR A SEWING RIB FOR ATTACHMENT TO INSOLES

Wallace C. Wright, Brookfield, N. H.

Application March 5, 1943, Serial No. 109,677

Term of patent 14 years

To all whom it may concern:

Be it known that I, Wallace C. Wright, a citizen of the United States and resident of Brookfield, county of Carroll, and State of New Hampshire, have invented a new, original, and ornamental Design for a Sewing Rib for Attachment to Insoles, of which the following is a specification, reference being made to the accompanying

drawing, forming part thereof, in which the figure is a perspective view of a sewing rib for attachment to insoles, on the stitch-receiving grooved side, showing my new design.

I claim:

The ornamental design for a sewing rib for attachment to insoles, as shown and described.

WALLACE C. WRIGHT.
